McDOWELL GRAVES, OF LOS ANGELES, CALIFORNIA, ASSIGNOR, BY MESNE ASSIGNMENTS, TO R. A. DALLUGGE, OF LOS ANGELES, CALIFORNIA.

VENDING-MACHINE.

1,310,988.

Specification of Letters Patent.

Patented July 22, 1919.

Application filed September 2, 1916, Serial No. 118,168. Renewed December 12, 1918. Serial No. 266,509.

To all whom it may concern:

Be it known that I, McDOWELL GRAVES, a citizen of the United States, residing at Los Angeles, in the county of Los Angeles, 5 State of California, have invented new and useful Improvements in Vending-Machines, of which the following is a specification.

This invention relates to vending machines and particularly to vending machines 10 for articles contained in boxes or otherwise forming a flat, box-like package; and it is an object of this invention to provide a simple and reliable mechanism for vending such articles. It is also an object to provide a 15 mechanism which may be cheaply and efficiently manufactured and a mechanism which will be effective and dependable in use.

20 In the following specification I explain the mechanism of my vending machine together with a coin controlled mechanism particularly adapted to operate this vending machine; but the coin controlled mechanism 25 is the subject matter of my co-pending application S. N. 118,169, filed Sept. 2, 1916, and of the claims therein. In this application I desire to particularly claim the vending machine itself; that is, the mechanism 30 which delivers out a package from the number of packages in the hopper.

The operation of delivering a package involves a simple back and forth movement of the parts. In a typical and preferred form 35 of apparatus, I provide a pivotally movable hopper from whose lower end the packages are delivered. A simple back and forth movement of the hopper causes the lowermost package to be delivered by causing 40 that package to move downwardly from one support or set of supports to another until it is entirely free of the hopper. Movement in one direction drops the package from an upper set of supports to a lower set of 45 supports and movement in the opposite direction frees the package and allows it to be finally delivered from the mechanism.

I describe a preferred form of machine in the following specification and illustrate the 50 same in the accompanying drawings in which: Figure 1 is a central vertical cross section of a preferred form of my machine; Fig. 2 is a vertical section of the lower part of the machine taken as indicated by line 55 2-2 on Fig. 1; Fig. 3 is a horizontal sec-

tion taken as indicated by line 3-3 on Fig. 1; and Fig. 4 is a central vertical cross section of the lower parts of the apparatus showing the position of the parts when half through the delivery operation.

In the drawings I show a suitable case 10 in which a hopper 11 is pivoted at 12 near its top and back side. Hopper 11 has two package supporting feet 13 at its bottom at its forward edge. The front of the 15 hopper is substantially open, as shown in the various views, the front being formed of two narrow side strips 14. The package supporting feet 13 are located at the opposite sides of the front behind these front 20 strips 14. The back of the hopper is cut away forming an edge at 15. Beneath this edge and projecting into the hopper through the cut away portion I place a stationary package supporting shelf 16. The vertical distance between edge 15 and shelf 16 is less than the vertical thickness of a package to be vended. The side walls of the hopper extend downwardly as shown at 11^a 25 below the feet 13 and edge 15; and a package supporting shelf 17 is carried at the lower end of the side walls, said shelf being normally below the stationary shelf 16. A pair of stop members 20 is mounted forward of the hopper and in such position that, when 30 the hopper is swung forwardly, the stop members will project into its front side at its lower end. Each of these members 20 has a lower package supporting foot 21 which 35 projects farther into the hopper.

With the foregoing described construction in mind, the operation of the device may be readily understood. In the first movement the hopper is swung forwardly to the position shown in Fig. 4. The first effect of this movement is to cause the edge 15 of the hopper to engage the rear upper edge of the lowermost package, as shown in dotted lines at 30, and to move the lowermost edge of the package off the stationary 40 shelf 16 and allow it to drop onto the hopper shelf 17, which has moved forwardly with the hopper; the forward edge of the package still resting upon the package supporting feet 13. When the package is in 45 this position the hopper cannot be moved rearwardly unless it is first moved farther forwardly. Any attempted rearward movement will not change the position of the package and will not prevent the package 50

being alternately delivered by further movement forward and then rearward. Further forward movement brings the forward edge of the package against the stop members 20 and causes the package to be moved rearwardly with relation to the hopper until its forward edge leaves the feet 13 and falls onto the stationary feet 21. Or, in other words, the package is held from further forward movement by stop members 20 while the feet 13 move out from under it. This position is shown in dotted lines in Fig. 4. When this position of the package is reached, the rearward motion of the hopper is begun. When the hopper moves rearwardly the package is prevented from rearward movement by its rear edge moving back against the stationary shelf 16. Consequently the movable shelf 17 merely moves rearwardly from under the rear edge of the package, whose forward edge is still resting upon the feet 21; and, when the shelf 17 has moved completely from under the rear edge of the package, the rear edge 25 drops and the package starts, rear edge first, down over the delivery chute 31.

I show in the drawing a simple coin-controlled mechanism for causing the desired movement of the delivery mechanism. A coin chute or slot 40 is mounted upon a shelf 41 attached to the lower front edge of the hopper 11, said shelf being below the package supporting feet 21. The shelf 41 has a coin passage or opening 42 through its forward edge directly beneath the chute 40. A coin fed into the chute 40 will drop down through the opening 42 (it is immaterial for the present how the coin is fed into chute 40). The coin passing through the opening 42 falls into an inclined trough 43, which is mounted upon a frame 44 pivotally mounted at 45. The frame 44 normally stands in a position shown in Fig. 1 with the coin trough 43 directly below the opening 42. When the coin is inserted it immediately falls to the position shown at C in Figs. 1 and 2. The frame 44 has a handle 46 projecting outside the case, and downward movement of the handle will cause forward movement of the upper end of the frame. Forward movement of the upper end of the frame, will, through the connection of the coin at C, cause forward movement of the shelf 41 and of the hopper to which it is attached. Once this forward movement is started, a hook 47, which extends out from the back of frame 44, will engage around the lower edge of a lip or flange 48 on shelf 41; and subsequent forward movement of the frame 44 will cause forward movement of the hopper through the medium of the hook 47 and lip 48. But if the frame 44 be moved forwardly without inserting a coin, the hook 47 in its forward movement will not engage the lip 48

but will pass underneath it. In other words, the coin forms a connection between the frame 44 and the hopper during the first part of the movement until the hook 47 engages lip 48; but as soon as this engagement has taken place, then the hopper may be moved forward through the medium of the hook 47. Now, as the shelf 41 and the coin trough 43 move forwardly, the coin passage 42 begins to occupy more and more such a position relative to the trough 43 as is illustrated in Fig. 4, the distance between passage 42 and trough 43 becoming greater than the diameter of the coin; with the result that the upper edge of the coin moves down, or drops down, out of the passage 42 and moves out of operative relation to the parts. The coin either snaps out of opening 42, or it may merely move down from the opening and then roll down the inclined trough 43. It will be noted that the coin is not released until the parts reach such a position that the hook 47 has first engaged lip 48 and then the package has fallen to the first moved position; *i. e.* its position with its forward edge still on feet 13 and its rear edge dropped onto shelf 17; in which position the package prevents rearward movement of the hopper. Consequently, it is impossible to loose the package after the coin is dropped, as it is then only possible to complete the forward stroke of the hopper, and the machine itself then completes the rearward stroke which delivers the package. A spring at 50 draws the frame 44 back to its normal position, and, through the medium of the engagement of the shoulder 47a with the lip 48, throws the hopper back to its normal position. It is during this last mentioned movement that the package is finally delivered. The coin must necessarily be discharged, from its position where it acts as a connective member, at the forward end of the movement; while it is necessary to complete the rearward movement before the package is delivered.

Having described a preferred form of my invention I claim:

1. In a vending machine, a stationary frame having a package supporting shelf, a horizontally movable hopper having package supporting parts opposite the stationary shelf, a movable package supporting shelf on the hopper beneath the stationary shelf, and a stationary package supporting member beneath the package supporting parts on the hopper.

2. In a vending machine, a frame, a horizontally movable hopper in said frame, said hopper having a package supporting part at its front lower edge, the back lower part of the hopper being cut away, a stationary package supporting shelf projecting into the hopper at the back opposite the package supporting part on the front of the hopper, the

vertical distance between said stationary shelf and the lower edge of the back of the hopper being less than the vertical thickness of a package to be vended, a package supporting shelf carried by the hopper beneath said stationary shelf at a distance therefrom less than the thickness of the package, and stationary package supporting means beneath the package supporting part on the front of the hopper at a distance below the same greater than the thickness of the package to be vended.

3. In a vending machine, a frame, a hopper pivoted at its upper end in said frame, said hopper having a package supporting part at its front lower edge, the back lower part of the hopper being cut away, a stationary package supporting shelf projecting into the hopper at the back opposite the package supporting part on the front of the hopper, the vertical distance between said stationary shelf and the lower edge of the back of the hopper being less than the vertical thickness of a package to be vended, a package supporting shelf carried by the hopper beneath said stationary shelf at a distance therefrom less than the thickness of a package, and stationary package supporting means beneath the package supporting part on the front of the hopper at a distance below the same greater than the thickness of the package to be vended.

4. In a vending machine, the combination of a movable package supporting part and a stationary package supporting part arranged opposite each other, another movable package supporting part movable with the first mentioned movable part and vertically

spaced from the said stationary supporting part by a distance less than the thickness of a package to be vended, and another stationary package supporting part vertically spaced from the first mentioned movable supporting part by a distance greater than the thickness of said package.

5. In a vending machine, a stationary frame, a normally vertical hopper mounted upon a horizontal pivot at its upper end on the frame, package supporting parts at the lower front edge of the hopper, the rear lower part of the hopper being open, a stationary package supporting shelf mounted upon the frame and projecting into the hopper at its back open portion opposite the front package supporting parts, so that a package may normally rest upon said package supporting parts and said shelf, the lower edge of the back of the hopper being below the upper edge of a package resting upon said shelf, a package supporting shelf carried by the hopper across its back side beneath the stationary shelf at a vertical distance therefrom less than the thickness of the package, and stationary package supporting parts beneath the front package supporting parts on the hopper at a distance therefrom greater than the thickness of said package.

In witness that I claim the foregoing I have hereunto subscribed my name this 17th day of August 1916.

McDOWELL GRAVES.
